UNITED STATES PATENT OFFICE.

ARTHUR ROSENFIELD, OF ST. LOUIS, MISSOURI.

SPARK PLUG.

Application filed May 10, 1920. Serial No. 380,265.

To all whom it may concern:

Be it known that I, ARTHUR ROSENFIELD, a citizen of the United States, residing at St. Louis, Missouri, have invented a certain 5 new and useful Improvement in Spark Plugs, of which the following is a full, clear, and exact description, such as will enable others skilled in the art to which it appertains to make and use the same, reference 10 being had to the accompanying drawings, forming part of this specification.

My invention relates to spark plugs such as are generally used for producing an electric spark for the ignition of the explosive 15 charges in the combustion chambers of internal combustion engines, the principal object of my invention being to generally improve upon and simplify the construction of the existing types of spark plugs, and particularly those forms of plugs which are provided with intensifying spark gaps.

Further objects of my invention are, to provide a relatively simple and efficient 20 spark plug that may be easily and cheaply produced, and the construction being such that the intensifying gap is under all conditions self-adjusting so that after the parts of the plug have been properly assembled, it will not be necessary to make any adjustments to produce the intensifying gap between the electrodes.

Further objects of my invention are, to provide a spark plug that can be readily assembled or taken apart; to provide one of 25 the electrodes of the plug with a ball and socket joint which enables the lower end of said electrode to automatically adjust itself upon the lower insulator, and with respect to the electrode carried by said lower insulator; and, further, to provide a plug 30 wherein the upper insulator is very firmly secured in position within the upper portion of the body of the plug.

With the foregoing and other objects in 35 view, my invention consists in certain novel features of construction and arrangement of parts, hereinafter more fully described and claimed, and illustrated in the accompanying drawings, in which—

Figure 1 is a vertical section taken through 40 the center of a spark plug of my improved construction.

Figure 2 is a horizontal section taken approximately on the line 2—2 of Figure 1.

Figure 3 is an elevational view of the cap 55 insulator that is arranged in the upper portion of the spark plug.

Figure 4 is an enlarged vertical section taken approximately on the line 4—4 of 60 Figure 1.

Figure 5 is a section similar to Figure 4 and showing a modified form of the electrode or current carrying member that is seated in the upper or cap insulator.

Referring by numerals to the accompanying 65 drawings which illustrate a practical embodiment of my invention, 10 designates the main body portion of the plug which is in the form of a substantially cylindrical shell of metal, the lower portion thereof being reduced in diameter and provided with an external thread 11 whereby the plug may be screwed into the wall of an internal combustion engine.

The upper portion of the wall of the shell 75 10 is internally threaded in order to receive the externally threaded lower end of a metal bushing 12. The enlarged upper portion of the shell 10 is provided with angular faces 13 adapted to receive a wrench or like 80 tool whereby the plug may be screwed into the engine cylinder and the bushing 12 is provided with angular faces 14 adapted to receive a suitable tool whereby said bushing is screwed into said shell.

Formed within the shell 10 between the larger upper portion and relatively small lower portion is a horizontally disposed annular shoulder 15 and bearing thereupon is a suitable gasket 16, preferably of metal, or 90 a combination of metal and asbestos. Bearing directly on top of this gasket is the underside of a relatively wide flange 17 that projects outwardly from the central portion of a core insulator 18. This insulator is 95 preferably formed of vitrified earthen ware, such as porcelain, and the upper surface of the annular flange 17 formed thereon is inclined or beveled as designated by 19. Bearing upon this inclined or beveled surface is 100 a gasket 20, preferably of metal, and bearing on top of said gasket is the beveled lower edge of the wall of the bushing 12.

The construction just described, and particularly the arrangement of the gaskets between the flange 17 of the core insulator and the shell 10 and bushing 12 maintains the core insulator in firm and substantial posi-

tion within said shell and provides fluid pressure tight joints between the assembled parts.

Extending axially through the core insulator 18 is an electrode 21, the upper end 22 thereof projecting a slight distance above the upper end of the body of said core insulator and the lower end of said electrode terminating a short distance below the skirt 10 of said insulator. Secured to the lower end of the shell 10 is a substantially L-shaped electrode 23, the free end of which terminates adjacent to the lower end of the electrode 21.

15 Fitting snugly within the bushing 12 and projecting a short distance above the upper end thereof is a cap insulator 24 in the lower portion of which is formed an upwardly projecting recess 25 and which latter, when the 20 parts are properly assembled, receives the upper portion of the core insulator 18.

Formed in the outer face of the lower portion of this cap insulator and at diametrically disposed points are bayonet joint 25 grooves 26 which are adapted to receive the inner ends of pins 27 that are seated in the bushing 12. Formed in the outer face of the lower portion of the cap insulator is a series 30 of annular grooves 28 and before the cap insulator is inserted in the bushing, these grooves, as well as the bayonet grooves 26, are filled with a suitable cement which, when dry and hard, very firmly secures the cap insulator within the bushing.

35 When the cap insulator is inserted into the bushing and said insulator is turned so that the inner ends of the pins 27 occupy the ends of the horizontally disposed portions of the bayonet grooves it will be practically impossible for said cap insulator to become disengaged from the bushing even though the cement should become loose.

Formed through the upper portion of the cap insulator is an aperture 29 and seated 45 therein is a short metal tubular member 30 that is provided on its lower end with an outwardly projecting flange 31, which latter bears against the bottom of recess 25. The upper end of member 30 is externally threaded 50 and screw-seated on this threaded portion is a nut 32 which, when tightened against the top of the cap insulator, very firmly anchors said member in said insulator. Member 30 is internally threaded and 55 passing therethrough is a short threaded rod 33, the lower end of which is connected by a ball and socket joint 34 to an inverted cup-shaped member 35 which latter is adapted to bear directly on top of the core insulator 18 60 around the projecting upper end 22 of electrode 21.

Screw-seated on the upper portion of the threaded rod 33 is a lock nut 36 that is adapted to bear directly on top of nut 32 to

lock the same against reverse movement, and 65 screw-seated on that portion of the rod above the lock nut 36 is a binding nut 37 that is adapted to secure the terminal portion of the electric connection that leads to the spark plug.

70 The extreme upper end of rod 33 is provided with angular faces 38 in order to be engaged by a wrench or like tool for the purpose of screwing said rod in either direction through member 30.

75 When the parts of my improved plug are assembled and the bushing 12 is screwed tightly into the shell 10, the beveled lower edge of the wall of said bushing bears directly on top of the gasket 20 and causes the flange 17 of the core insulator to bear with pressure against gasket 16, thereby firmly holding the core insulator in a central position within the shell and forming joints 80 between the cooperating parts which will effectually prevent leakage of gas or fluid pressure through the plug.

85 When the parts of the plug are assembled, the threaded rod 33 is screwed through member 30 until the lower edge of the inverted cup-shaped member 35 bears on top of the core insulator, and the space between the wall of said member 35 and the projecting upper end 22 of the electrode 21 forms an intensifying spark gap for the 90 current in traveling through the plug must jump this gap with the result that a relatively large or "fat" spark is produced between the ends of the electrodes 21 and 23, and which spark is effective in igniting the 95 explosive charge in the combustion chamber of the engine.

100 Inasmuch as the cup-shaped member 35 is connected by a ball and socket joint to rod 33, said member will automatically adjust itself to any variation on the upper surface of the core insulator due to inaccuracies of manufacture or for any other cause and this arrangement provides for an intensifying 105 spark gap that is fixed or of the same width 110 under all conditions.

115 In Figure 5 I have shown a modified construction wherein the inverted cup-shaped member that encloses the upper end of the electrode carried by the cap insulator is normally under spring tension, such arrangement being effected by the use of a tubular member 38 that is seated in the center of the cap insulator and said member being connected directly to the threaded rod 39 that 120 projects upwardly through said cap insulator. Arranged to slide freely through the lower portion of the tubular member 38 is a pin 40, the lower end of which is connected by a ball and socket joint 41 to an inverted 125 cup-shaped member 42 and positioned within the tubular member 38 and bearing on top of pin 40 is a compression spring 43.

A spark plug of my improved construction can be easily and cheaply manufactured, and the construction and arrangement of the current carrying parts is such as to produce 5 an intensifying gap that is constant under all conditions. Such a gap is effective in intensifying the firing spark that is produced between the terminals of the electrodes that are disposed within the combustion chamber of the engine, and as a result, 10 a firing spark of sufficient intensity is produced which will insure the ignition of the explosive charge. When the parts of the plug are properly assembled, the space within 15 recess or chamber 25 is practically air-tight and after the plug has been in operation for a short period of time, the greater portion of the nitrogen and oxygen within this air tight chamber will be consumed by the 20 spark produced by the intensifying gap between the parts 22 and 35 and as a result of this absence of atmospheric resistance, the efficiency of the device in operation will be materially increased.

25 It will be readily understood that minor changes in the size, form and construction of the various parts of my improved spark plug can be made and substituted for those herein shown and described, without departing 30 from the spirit of my invention, the scope of which is set forth in the appended claims.

I claim as my invention:

1. In a spark plug, a shell, an insulating 35 core positioned therein, an electrode extending through said core, a cap insulator enclosing the upper portion of said insulating core, an electrode carried by said cap insulator and adapted to cooperate with the electrode carried by the insulating core to form 40 an intensifying spark gap, a ball on the end of said cap electrode, and a cooperating socket member bearing against said core.

2. In a spark plug, a shell, an insulating 45 core positioned therein, an electrode extending through said core, a cap insulator enclosing the upper portion of said insulating core, a spring-pressed electrode carried by said cap insulator, and said last mentioned 50 electrode being connected with said core by means of a ball and socket joint.

3. In a spark plug, a pair of insulators, electrodes carried by said insulators and one of which electrodes is provided with a ball and socket joint whereby it is self-adjusting with respect to the opposite electrode and the insulator in which said opposite electrode is positioned.

4. In a spark plug, a shell, an insulating 60 core positioned therein, an electrode carried by said core, a bushing removably positioned in the shell, an insulator carried by said bushing and partially enclosing the upper portion of the first mentioned insulator, and

an electrode carried by the insulator in said bushing, the lower end of said last mentioned electrode being adapted to bear on the upper portion of the insulator carried by the shell, and the electrode that is carried by the insulator in said bushing being provided with a ball and socket joint.

5. In a spark plug, a bushing, an electrode carrying insulator positioned in said bushing, and there being a bayonet joint between said insulator and bushing.

6. In a spark plug, an electrode terminating in a ball, a socket member mounted on said ball and provided with an annular rim projecting away from said electrode, an insulator seated against said rim, and an electrode carried by said insulator and projecting beyond same within the recess formed by said rim.

7. In a spark plug, a bushing, an electrode carrying insulator positioned in said bushing, there being annular grooves formed in the outer face of said insulator, which grooves are adapted to receive cement for securing the insulator to said bushing, and there being a bayonet joint between said insulator and bushing.

8. In a spark plug, a shell, an insulating core positioned therein, an electrode extending through said core, a bushing removably positioned in said shell, a cap insulator carried by said bushing, a current carrying member passing through said cap insulator, and a recessed member connected by a ball and socket joint to the lower end of said current carrying member and which recessed member encloses the upper end of the electrode that is carried by the core insulator and is adjustably seated on said core insulator by means of said joint.

9. In a spark plug, a pair of insulators, electrodes carried by said insulators, and an inverted cup-shaped member adapted to partially enclose one end of one of said electrodes and self-adjusting about the latter by means of a ball and socket connection to the other of said electrodes.

10. In a spark plug, a pair of insulators, an electrode extending through one of said insulators, an electrode adjustably positioned in the other insulator, and said adjustable electrode being provided with a ball and socket joint whereby it is self-adjusting with respect to the opposite electrode and the insulator in which said opposite electrode is positioned.

11. In a spark plug, a pair of insulators, electrodes carried by said insulators, the adjacent ends of said electrodes between said insulators being spaced apart to form an intensifying spark gap, and one of said electrodes being provided with a ball and socket joint whereby it is self-adjusting with respect to the opposite electrode.

12. In a spark plug, an insulator, and a current carrying member adjustably seated thereon by means of a ball and socket joint.
13. In a spark plug, a pair of current carrying members, the adjacent ends of which are spaced apart to provide an intensifying spark gap, and one of said electrodes being provided with a ball and socket joint whereby its end portion is self-adjusting with respect to the adjacent end portion 10 of the opposite electrode.

In testimony whereof I hereunto affix my signature this 8th day of May, 1920.

ARTHUR ROSENFIELD.
